(57) **CLAIM**

The ornamental design for a carabiner, as shown and described.

DESCRIPTION

FIG. 1 is a perspective view of a carabiner showing our new design;

FIG. 2 is a left side view thereof;

FIG. 3 is a right side view thereof;

FIG. 4 is a front side view thereof;

FIG. 5 is a rear side view thereof;

FIG. 6 is a top view thereof;

FIG. 7 is a bottom view thereof; and,

FIG. 8 is a perspective view of the carabiner of FIG. 1 shown in a position of use with the environmental subject matter of a carabiner gate.

The broken lines shown in the drawings depict portions of the carabiner that form no part of the claimed design. The additional broken lines in FIG. 8 depict environmental subject matter that forms no part of the claimed design.
